Application June 22, 1951, Serial No. 233,076

10

3 Claims. (Cl. 144—32)

This invention relates to the manufacture of brush rigging for a dynamoelectric machine and its object is to provide a machine for facilitating the assembling of a brush holder, a brush and a brush lead wire which are attached together by a screw extending through a hole in a terminal clip to which the lead wire is attached, through a hole in the brush and received by a threaded hole in the brush holder.

In the disclosed embodiment of the invention, the machine comprises a conveyor which is automatically indexed to move a plurality of workholders successively to stations where, respectively, parts are manually or automatically placed upon the workholder and a screw is automatically moved through aligned holes in the brush lead wire terminal clip and in the brush and is threaded through the aligned, tapped hole in the brush holder. Each workholder supports a vertically movable pin which is caused initially to extend above the workholder so as to be received by the hole in the brush holder, the hole in the brush and the hole in the lead wire clip as these parts are successively assembled upon the holder. At a station ahead of the screwdriver station, the pin is pushed down so that its upper end is slightly above the lead wire clip. At the screwdriver station, the screw which has been received by the screw catcher of the screwdriver is forced down by the screwdriver blade and thereby is caused to engage the pin to push it down as the screw moves down through the holes in the lead wire clip, brush and brush holder. In this way, the pin pilots the screw downwardly through the holes in the lead wire clip and the brush to the tapped hole in the brush holder; and the screwdriver blade threads the screw into said tapped hole. At a station following the screwdriver station, the pin is pulled downwardly still further to clear the brush holder. At a following station the assembled parts are unloaded or pushed from the work holder.

Further objects and advantages of the present invention will be apparent from the following description, reference being had to the accompanying drawings wherein a preferred embodiment of the present invention is clearly shown.

In the drawings:

Fig. 1 is a view of an assembly of two brushes and associated parts which can be assembled by the machine.

Figs. 2 and 3 are side and front views respectively of a single brush and associated parts which can be assembled by the machine.

Fig. 4 is a plan view of a work holder support with two work holders mounted thereon.

Fig. 5 is a front view thereof.

Fig. 5A shows a portion of the work holder support as seen in Fig. 5 with work pieces in position thereon.

Figs. 6 and 7 are respectively sectional views on the lines 6—6 and 7—7 of Fig. 5.

Figs. 8, 9 and 10 are respectively front, side and top views of a member 31 included in a work holder.

2

Figs. 11 and 12 are top and end views respectively of a part 48 included in a work holder.

Figs. 13 and 14 are front and side views respectively of a part 47 included in the work holder.

Figs. 15 and 16 are respectively plan and side views of the machine frame.

Figs. 17 and 18 are drawn to a larger scale than Figs. 15 and 16.

Fig. 17 is a view in the direction of arrow 17 of Fig. 18 and Fig. 18 is a view in the direction of arrow 18 of Fig. 16.

Fig. 19 is a fragmentary view in the direction of arrow 19 of Fig. 18 and is drawn to a larger scale.

Fig. 20 is a view in the direction of arrow 20 of Fig. 19.

Fig. 21 is a diagram of a clutch control associated with Figs. 19 and 20.

Fig. 22 is a side view of a mechanism for elevating the work holder pins which are down in Fig. 22.

Fig. 23 is a view in the direction of arrow 23 of Fig. 22.

Fig. 24 is a view similar to Fig. 22 showing the pins 36 pushed up.

Figs. 25 and 25a form a side view of a washer feeding mechanism.

Figs. 26 and 27 are views respectively in the direction of arrows 26 and 27 of Fig. 25.

Fig. 28 is a side view of a load checker.

Fig. 29 is a view in the direction of arrow 29 of Fig. 28.

Fig. 30 is a view in the direction of arrow 30 of Fig. 28.

Fig. 31 is an enlarged sectional view on line 31—31 of Fig. 29.

Fig. 32 is a side view of a screwdriver.

Fig. 33 is a sectional view on line 33—33 of Fig. 32.

Fig. 34 is an enlarged longitudinal sectional view on line 34—34 of Fig. 39 showing the screw catcher in closed position.

Fig. 35 is a view similar to Fig. 34 showing the screw catcher in open position.

Fig. 36 is a fragmentary view in the direction of arrow 36 of Fig. 35.

Fig. 37 is a view in the direction of arrow 37 of Fig. 36 and shows the screw catcher in closed position.

Fig. 38 is a view similar to Fig. 35 and shows also the screwdriver blade forcing a screw *s* against a pin 36.

Fig. 39 is a fragmentary front view of the screwdriver looking in the direction of arrow 39 of Fig. 32.

Fig. 40 is a continuation of Fig. 32 and shows a mechanism for operating a station centering device associated with the screwdriver.

Figs. 41 and 42 are sectional views respectively on line 41—41 and 42—42 of Fig. 32.

Fig. 43 is a view in the direction of arrow 43 of Fig. 42.

Fig. 44 is a sectional view on line 44—44 of Fig. 32.

Fig. 45 is a side view of a mechanism for lowering the workholder pins.

Fig. 46 is a view in the direction of arrow 46 of Fig. 45.

Fig. 47 is a view in the direction of arrow 47 of Fig. 46.

Fig. 48 is a view similar to Fig. 45 showing the workholder pin supporting rods 35 in lowest position.

Fig. 49 is a side view of a work unloading mechanism.

Fig. 50 is a view in the direction of arrow 50 of Fig. 49.

Fig. 51 is a view in the direction of arrow 51 of Fig. 49.

Fig. 52 is a sectional view on line 52—52 of Fig. 49.

Fig. 53 is a side view of a workholder clean-out mechanism.

Fig. 54 is a view in the direction of arrow 54 of Fig. 53.

Fig. 55 is a fragmentary view in the direction of arrow 55 of Fig. 53.

Fig. 56 is a view showing the front side of a workholder in association with a switch which, in case of failure to unload the work at the unloading station, is operated in a manner to cause the machine to stop.

Figs. 57 through 61 are views of cams and valves or switches operated thereby.

Fig. 62 is a chart of relays which are included in the wiring diagram shown in Figs. 63 and 64.

Figs. 63 and 64 together constitute a wiring diagram of the electrical controls of the machine.

Fig. 65 is a timing chart.

Work performed by the machine

Referring to Figs. 1, 2 and 3, the machine facilitates the assembling of parts which include a U-shaped brush holder 10 having arms, each of which provide holes 11 for receiving a pivot pin of the brush rigging. Holder 10 supports a brush 12 and a terminal clip 13 attached to a lead wire 14 which is attached to a terminal clip 15. These parts are attached to the holder 10 by a screw 17 which may be of the self-tapping type requiring no lock washer, or if it is a plain screw, a lock washer 16 is used. As shown in Fig. 1, there are two brush assemblies which are connected electrically by a wire 18. These assemblies can be made while the parts are supported by workholders of adjacent workholder supports. The single brush assembly shown in Figs. 2 and 3 is made while the parts are supported on one workholder.

Workholders

Each workholder 20 shown in Figs. 4 and 5 comprises a horizontal plate 21 and a vertical plate 22. Plate 21 carries rollers 23 and plate 22 carries a roller 24. Referring to Fig. 22 the rollers 23 are received between bars 25 and 26 attached to a bar 27 supported by bar 28 which is attached to bars 29 and 30. Bar 29 receives roller 24 and bar 30 is engaged by the side of roller 24 to maintain the workholder support plate 22 in vertical position. The parts 25 through 30 comprise parts of track sections. As shown in Fig. 15 there are two long track sections T1 and two short track sections T2.

Each workholder support 20 supports two workholder blocks 31 shown separately in Figs. 8, 9 and 10. As shown in Fig. 7 each block 31 has a threaded shank 32 which extends through the horizontal plate 21 and receives a nut 33 by which the workholder is clamped to that plate. The block 31 supports a vertically movable rod providing at its upper end a pin 36 which is received by holes in brush holder 10, brush 12 and clip 13 (Fig. 1) thereby locating these parts in such positions that their holes are in alignment. The rod 35 provides grooves 37 and 38, each adapted to receive a ball 39 which a spring 40 urges into the groove, the spring being retained by a plug 40a. When the pin 36 is in the upper position shown in Fig. 7, the groove 38 receives the ball 39. When the pin 36 is in the lowest position the groove 37 receives the ball 39. Each rod 35 has a flat 35a (Fig. 5) providing a long notch, the ends of which are engageable by a stop screw 35b.

As shown in Fig. 8, the block 31 provides a nest 34 for receiving the brush holder 10, said nest locating the brush holder so that its yoke 10a is horizontal. The holes 11 in the brush holder arms are received by a pin 11a (Fig. 5) when the brush holder is moved horizontally to place it upon the nest 34. Before the brush holder is placed manually upon the nest 34 the pin 36 is down. The pin 36 is caused to move up into the position shown in Fig. 7 before brush 12 is placed upon the brush holder, the pin 36 being received by the hole in the brush. Then the terminal clip 13 is placed upon the brush 12, the pin 36 being received by the hole in the terminal 13. Terminal 13 is received by a notch 41 provided by block 31 and it is retained by a latch 42 pivoted on a pin 43 and

urged clockwise by plunger 44 which a spring 45 urges upwardly. A plate 47 shown in Figs. 13 and 14 which is attached to the block 31 supports a bar 48 shown in Figs. 11 and 12. A pivot screw 49 supported by plate 47 supports a lever 50 which is urged against a pin 51 supported by plate 47 by a spring located between lever 50 and bar 48. Plate 47 supports a rod 52. During the operation of a screwdriver to place the screw 17 (Fig. 1) and thread it through the hole in the brush holder 10, a wedge, to be described, is caused to descend between rod 52 and surface 50a of lever 50 to cause it to press against the brush 12 and the latter against the pin 36. Fig. 4 shows a plate 55 which has a threaded shank 56 (Fig. 5) which extends through a hole in plate 21 and receives a nut 57 by which the plate 55 is secured to plate 21. Plate 55 provides a vertically extending rod 58 which is used for station centering purposes to be described.

Machine frame and conveyor

Referring to Figs. 15 and 16, the track sections T1 and T2 which guide the workholder are supported by plates 60 supported by spacers 61 supported by channels 62 which are supported above the floor by leg frames 63 and by a box-like structure which includes horizontal plates 64 and 65 (Figs. 17 and 18), and by vertical plates 66 and 67. The channels 62 are spaced by tubes 68 (Fig. 18) through which there pass bolts 69 which receive nuts 70, the tightening of which clamps the channels against the ends of spacing tubes 68.

Referring to Figs. 15 and 16, the channels 62 support plates 71 which support bearings 72 for shafts 73 attached to sprockets 74 around which there pass two conveyor chains 75 which move in directions indicated by arrows 75a, 75b. The sprocket 74 which is the upper left hand one in Fig. 15 is the driving sprocket marked 74d in Figs. 17 and 18. Its shaft 73d is journaled also in a bearing 76 provided by a plate 77 supported by vertical plates 78 and 79 supported by plate 71 as shown in Figs. 17 and 18. This structure includes end plates 80 and 81 and a partition plate 82. Shaft 73d is connected with a bevel gear 83 meshing with a bevel gear 84 connected with a shaft 85 journaled in bearings provided by plates 80 and 82 and connected with a sprocket 86 meshing with a chain 87 which engages a chain slack-takeup sprocket 88 supported by an adjustable bracket 89 and meshing with a sprocket 90 attached to a shaft 91 supported by a bearing bracket 92 attached to plate 66.

An electric motor M1 drives a shaft 93 through a speed reducer contained in a housing 94 supported by plate 65. Shaft 93 is connected by a coupling 93a with a shaft 95 journaled in a bearing bracket 96 supported by a plate 66. A torque limiting clutch 97 connects shaft 95 with a sprocket 98 which meshes with a chain 99 meshing with a sprocket 100 coaxial with shaft 91 and with a sprocket 101 coaxial with a shaft 102. Chain 99 is received also by a slack take-up sprocket 103 supported by a bracket 104 adjustable on plate 66. In Fig. 18 the circles marked I and II represent clutches. Clutch I when tripped connects sprocket 100 with shaft 91. Clutch II when tripped connects sprocket 101 with shaft 102. The details of these clutches and the mechanisms for tripping them are disclosed in application S. N. 192,912, filed October 30, 1950. During each rotation of shaft 102, clutch I is tripped automatically and disengages automatically at the end of one-third revolution of shaft 91 thereby causing the workholders connected with conveyor chains 75 to move a distance equal to the spacing of the workholders as shown in Fig. 17. Shaft 102 (Fig. 16) is connected by a coupling 102a with a cam shaft 105 supported by bearings 106 some of which are supported by brackets 107 supported by channels 62.

Referring to Figs. 19, 20 and 21, plate 66 supports a shaft 110 connected with a pawl 111, the point of which is received by a notch 112 of a lever 113 pivotally supported at 114 by plate 66. When pawl 111 is turned

counterclockwise (Fig. 21), a spring 115 moves the lever 113 counterclockwise to effect, through action of a link 116, counterclockwise movement of a latch lever 117 to disengage it from a clutch disc 118. This action releases the disc and causes it to be connected with sprocket 101 as disclosed in the application referred to. Thus the sprocket 101 is connected with cam shaft 105. If, before one revolution of cam shaft 105 the pawl 111 is not permitted to return to the normal position shown in Fig. 21, the cam shaft will continue to rotate. The disengagement of clutch II is effected by returning the pawl 111 to normal position so that it will be in position to be received by the notch 112 of lever 113 as it is rotated to the position shown by the action of a roller 119 carried by clutch disc 118. Therefore if the lever 113 is retained by pawl 111 in advance of the end of one revolution, the clutch will be disengaged and cam shaft 105 will stop in home position.

The mechanism for controlling pawl shaft 110 comprises a lever 120 attached to shaft 110 and connected by link 121 (Fig. 19) with a lever 122 pivotally supported at 123 by a plate 124 which is supported by plate 64. Lever 122 is connected with a lever 125 which a spring 126 urges counterclockwise and link 121 downwardly to locate pawl 111 in clutch disengaging position. Lever 125 carries a pin 127 received by slot 128 provided by a link 129 connected at 130 with a lever 131 attached to a shaft 132. To trip clutch II, shaft 132 is rotated counterclockwise by a control lever 133 or by energization of a solenoid S1, the armature 134 of which is connected by a link 135 with link 121.

Shaft 132 is moved clockwise for the purpose of causing disengagement of clutch II by energization of a solenoid S2, the armature 136 of which is connected by link 137 and pin 138 with a lever arm 139 attached to shaft 132. As shown in Fig. 20 armature 136 has moved toward solenoid S2 to effect clockwise movement of shaft 132 to stop position indicated by the word "Stop" in Fig. 19. Clockwise rotation of shaft 132 is limited by engagement of an arm 140 of shaft 132 with a fixed pin 141. In the stop position, arm 140 engages the plunger 142 of a switch SW19. A switch SW18 is normally held closed by a spring 144 which urges a lever 145 against the plunger 146 of this switch. Lever 145, which is pivoted at 147, has an arm 148 carrying a pin 149 which pivotally supports a bar 149a which a spring 149b, connecting bar 149a and arm 148, urges clockwise against a stop surface 149c of arm 148. During movement of shaft 132 from "stop" to "start" position, the arm 140 engages bar 149a and arm 148 is caused to rotate clockwise until plate 140 clears bar 149a. Therefore during counterclockwise rotation of shaft 132 switch SW18 is momentarily opened and is closed again by the action of switch 144.

Station 2—push up pin

At station 1 (Fig. 15) the brush holders are placed upon the nests of the workholders. At station 2 the pins are pushed up automatically by the mechanism shown in Figs. 22-24. A plate 150 supports a cylinder C1 enclosing a piston connected by rod 151 with a plate 152 carrying bushings 153 which slide on guide rods 154 attached to plate 150. Plate 152 carries two rods 155 for engaging the rods 35 which support the pins 36. When pressure fluid is admitted to the lower cylinder of C1 the rod 155 moves from the position shown in Fig. 22 to that shown in Fig. 24 to raise the rods 35 and pins 36 to the position shown in Fig. 24. The rods 35 move through the screw receiving holes of the brush holders 10.

Plate 150 supports a bracket 156 which supports a rod 157 providing a pivot for a hub 158, providing levers 159 and 160 for engaging the brush holders 10 and providing lever arms 161 and 162. Arm 161 is connected with a clevis 163 connected with a rod 164 which passes through a hole 165 in a bracket 166 attached to plate 152 and receives a nut 164a which, in the lower position

of plate 152, is engaged by bracket 166 to hold the lever 159 and 160 in the position shown in Fig. 22 against the action of a spring 167 surrounding a rod 168 connected with lever 162 and confined between bracket 156 and clevis 169 of rod 168. Therefore, spring 167 urges the levers 159 and 160 clockwise so that nut 164a is urged against bracket 166 when plate 152 is in the position shown in Fig. 22. When plate 152 moves into the position shown in Fig. 24 the spring 167 causes the levers 159 and 160 to bear yieldingly against the brush holders 10 to press them against the plate 47 so as to insure alignment of the holes in the brush holders with the pins 36 in advance of movement of these pins through the holes in the brush holders.

Stations 5 and 6—washer feeders

In the vicinity of station 3 (Fig. 15) the brushes 12 are placed upon the brush holders, the pins being received by the holes in the brushes. At station 4 the lead wire terminal clips are placed upon the brushes, the pins being received by the holes in the clips which are retained by the latches.

Figs. 25-27 show one of the two washer feeder mechanisms. A chute 170 receives washers from a motor driven hopper feed (not shown). Chute 170 is supported at its lower end by bracket 171. The washers are permitted to move one at a time to the lower end of the chute by a release mechanism like that shown in the copending application of Burge et al., S. N. 192,912, filed October 30, 1950. This mechanism includes blades 172 and 173 carrying respectively pins 174 and 175 which are caused alternately to move into the path of movement of the washers by a mechanism which comprises a cam 176 pivoted at 177 and having a lever arm 178 connected by link 179 with a lever 180 attached to a shaft 181 supported by a bracket 182 and connected with a lever 183, connected by a link 184 with a lever 185 pivoted at 186 on a bracket 187 and carrying a roller 188 which a spring 189 urges against a cam 190 operated by a cam shaft 105 which turns counterclockwise in Fig. 25A. After indexing the conveyor the cam 190 turns to present its lower land to roller 188 to permit spring 189 to move levers 185 and 178 counterclockwise to cause operation of cam 176 to cause release of a washer 16 which descends to the lower end of the chute which it is received by the hook 191 of a lever 192 pivoted at 193 and urged counterclockwise by a spring 194 confined between a clevis 195 attached to lever 192 and a clevis 196 connected at 197 with an arm 198 of cam 176. A plate 200 supports a cylinder C2 containing a piston connected by rod 201 with a block 202. When pressure fluid is admitted to cylinder C2, the block 202 rises to engage a rod 35 carrying a pin 36 which is then aligned with the washer 16. The rod 36 is lifted higher than shown in Fig. 24 so that the rod will pass through the washer 16. While the pin 36 is in the uppermost position, lever 192 is caused to move clockwise so that the washer can pass downwardly while being guided by the pin 36 to a position upon the terminal clip. Then pressure fluid is admitted to the upper end of cylinder C2 to retract the block 202 before the next indexing operation takes place.

Stations 7 and 9—load checker

Referring to Figs. 28-31 a bracket 210 supports a rod 211 providing a pivot for a lever 212 connected by a link 213 with a lever 214 pivoted at 215 on a bracket 216 and carrying a roller 217 which a spring 218 urges against a cam 220 rotated counterclockwise by the cam shaft 105. Since each workholder support 20 carries two workholders the lever 212 provides a pad 221 supporting two screws 222 each retained by a nut 223 as shown in Fig. 31. Each screw 222 provides a recess 224 for receiving the upper end of a pin 36 and for causing the pin 36 to move downwardly from its uppermost position during counterclockwise movement of lever 212 which occurs after the in-

dexing operation. The screw 222 moves down until it engages a washer 16 located upon a terminal clip 13 located upon a brush 12 located upon a brush holder 10. If all the required parts are present upon the workholder the operation of passing a screw through the aligned holes of the washer, clip and brush and the threading of the screw into the brush holder will take place at the next station where a power driven screwdriver is located. If any of the parts to be assembled are missing, the lever 212 can move far enough counterclockwise to cause the operation of a switch SW3 for station 7 and switch SW4 for station 9.

If self-tapping screws are used to tap the screw receiving holes for brush holders 10, the washers 16 are omitted. In such case the washer feeders shown in Figs. 25-27 are omitted. Then the switch is so adjusted in its mounting bracket that it will not be actuated when the screw 222 engages the terminal clip 13 if it is present. If the washer is omitted the pin 36 will be moved until its upper end is at a distance above the clip 13 which would be the same as the distance above the washer 16 if a washer is used in the assembly. In any event, a function of the load checker is to move the pin 36 downwardly so that its upper end is slightly above the upper surface of the washer 16 if a washer is used, or slightly above the upper surface clip 13 if a washer is not used. This location of the pin 36 is desirable since a function of the screwdriver as shown in Fig. 38 is to move the pin 36 downwardly as the screw moves downwardly to be received by the holes in the washer, if present, the terminal clip, brush and brush holders.

If the pins 36 should stick in upper position in the workholders, lever 212 would not be moved counterclockwise (Fig. 28) by spring 218 and switches SW12 (at station 7) and SW13 (at station 9). Therefore the machine would be stopped by means to be described.

Stations 8 and 10—screwdrivers

The screwdrivers at stations 8 and 10 are substantially alike. Referring to Fig. 44, a plate 230 supports a sleeve 231 receiving a sleeve 232 supporting bearings 233 for a shaft 234 provided by the lower end of a post 235 which, as shown in Fig. 32, carries a bracket 236 supporting an electric motor referred to as M2 for screwdriver #1 and M3 for screwdriver #2. Motor M2 drives a pulley 237 connected by a belt 238 with a pulley 239 rotatably supported by bracket 236. The hub of the pulley 239 has a splined connection with a quill shaft 240 which through a clutch, not shown, drives the screwdriver blade 241 shown in Fig. 38. The shaft 240 and the blade 241 are lowered and raised by vertically movable sleeve 242 which is connected with an arm 243 which is connected with a piston in a cylinder C3. A spring in cylinder C3 normally holds the arm 243 in upper position shown in Fig. 32. Pressure fluid is admitted to the upper end of cylinder C3 by the opening of a valve V3 having a plunger 244 which is engaged by a lever 245 attached to the armature 246 of a solenoid S3 for station 8 (S4 for station 10) which is energized after an indexing operation to cause downward movement of shaft 240 and screwdriver blade 241 to cause the screw 17 to move downwardly in Fig. 38 to move the pin 36 down as the screw passes through the holes in the washer 16, clip 13, brush 12 and brush holder 10. By engagement of the screwdriver blade clutch, at least by the time the screw 17 arrives at the brush holder 10, the screw is turned by the blade 241 to thread it through a previously tapped hole in brush holder 10 or, if the screw 17 is of the self tapping kind, it will be forced into a slightly smaller hole in brush holder 10 and the hole in the brush holder will be tapped as the screw turns.

The screw 17 which is engaged by the blade 241 has been previously delivered by hopper feed, not shown, to a screw catcher 250 which comprises a head disc 251 (Fig. 34) and two blades or arms 252 are so biased that they spread apart when permitted to do so as shown in

Fig. 35. When the screw 17 is received by the screw catcher the arms 252 are held more closely together as shown in Fig. 34. The arms 252 are notched at 253 to provide an opening through which the screw passes from the magazine chute to the screw catcher with the screw head up and the screw shank down so that the head rests upon flanges 254 of the arms 252. The arms are held in closed position by virtue of the engagement of their cylindrical bosses 255 with the inner cylindrical wall 256a of a block 256 received by a fixed sleeve 257 which is supported by a fixed sleeve 258 supported by a bracket 259a fixed to a bracket 259 (Fig. 32). Block 256 is limited in its vertical movement relative to sleeve 257 by a flange 260 of block 256 engaging a flange 261 of a block 262 which a screw 263 fixes to sleeve 257 so that upward movement of block 256 is limited. Downward movement of block 256 is limited by engagement of its flange 260 with the upper surface of sleeve 257. The head 251 of the screw catcher is secured by nut 265 to the lower end of a sleeve 266 vertically movable along sleeve 242. Sleeve 242 (Fig. 39) supports a bracket 267 providing a pivot at 268 for a lever 269 providing a projection 270 for engaging a collar 271 at the upper end of sleeve 266. As sleeve 242 moves down the projection 270 engages collar 271 to push the sleeve 266 down. The reaction between collar 271 and projection 270 tends to cam the lever 269 counterclockwise but such motion is limited by the engagement of its projection 272 with the surface 273 of bar 274 supported for vertical movement of bracket 273 which fits the bar 274 so closely that movement of bar 274 is resisted by friction. Bar 274 provides a fork 276 for engaging the block 256 for a purpose to be described. The sleeve 266 can move down with the sleeve 242 until the projection 272 of lever 269 arrives adjacent the beveled surface 277 of bar 274. Then the arm 269 can swing away from the flange 271 of sleeve 266 so that sleeve 266 does not move down while the screwdriver blade is passing the screw 17 through the parts to be assembled.

The downward movement of sleeve 266 as effected by downward movement of sleeve 242 causes movement of the screw catcher 250 from the position shown in Fig. 34 to that shown in Fig. 35. During this movement the bosses 255 of the screw catcher arms 252 have arrived at the portion 256b of the larger internal diameter of the block 256. Therefore the arms 252 are permitted to move apart to release the screw. During downward movement of the screw 17 it meets with light frictional resistance from the pin 36 and then with greater resistance as the screw 17 engages the brush holder 10. At this time the clutch connecting the quill shaft 240 with the blade 241 is caused to engage so that the screw 17 will be rotated so as to be threaded through a previously tapped hole in holder 10 or to cut its own tapped hole as it rotates by power received from the screwdriver.

In order to insure alignment of the screw with the holes in the work at the screwdriver station a screwdriver centering mechanism is provided. This includes a cam 280 (Fig. 40) driven counterclockwise by the cam shaft 105 and engaged by roller 281 carried by lever 282 pivoted at 283 on a bracket 284 and connected by link 285 with a lever 286 (Fig. 32) pivoted at 287 on a bracket 288 supported by plate 230. Lever 286 is connected by a link 289 with a lever 290 pivotally supported by a rod 290a supported by bracket 259. Lever 290 carries a plate 291 (Fig. 41) providing a notch 292 for receiving the rod 58 (Fig. 4) attached to the workholder support at the screwdriver station. The upper end of rod 58 is beveled so that as the lever 290 moves clockwise into the position shown in Fig. 32, the plate 291 may be cammed edgewise slightly and thereby cause a rotation of post 235 which supports the bracket 259 in order to align the screwdriver blade 241 with the holes in the work supported by the workholder at this station. The screwdriver supporting post 235 can rotate a slight amount to effect this alignment. Limited rotary movement of the post is permitted by

virtue of two aligned horizontal screws 295 (Figs. 32 and 41) supported by a plate 296 attached to sleeve 232. The ends of these screws are spaced apart a distance slightly greater than the thickness of a plate 297 attached to a bracket 298 attached to post 235. These screws 295 are so adjusted as to effect approximate alignment of the screwdriver blade with the holes in the work supported at the screwdriver station. The spacing between the screw 295 is such as to permit exact alignment of the screwdriver blade by virtue of the engagement of plate 291 with the rod 58. The roller 281 (Fig. 40) is yieldingly engaged with cam 280 by a spring 299 (shown on Fig. 32) which urges levers 286 and 282 counterclockwise.

Before the screw is caused to move through the holes in the parts upon the workholder, it is desirable that the brush then receiving the pin 36 be urged toward the left as viewed in Fig. 38. This is effected by a movement of wedge 300 (Fig. 43) having an inclined surface 301 which engages the surface 50a (Fig. 5) of lever 50 and a vertical surface 302 which engages the rod 52 of the workholder. Therefore, as the wedge 300 is received between the rod 52 and the lever 50, the brush is urged to the left in Fig. 38. The wedge 300 has a thread shank 303 which passes through the free end of a lever 304 and is retained by nut 305. Lever 304 extends from a hub 306 (Fig. 42) which is pivotally supported upon a rod 306a supported by bracket 259 (Fig. 44). The application of the wedge 300 is effected by clockwise movement of lever 304 (Fig. 32). This movement is effected yieldingly by a spring 307 which surrounds a rod 308 extending through a hole in bracket 309 and attached to a clevis 310 which a pin 311 connects with a lever 312 integral with lever 304 as shown in Fig. 42.

Lever 304 provides a bracket 315 supporting a roller 316 engageable by plate 291 of lever 290. When lever 290 moves counterclockwise to clear the rod 58, plate 291 engages roller 316 to move lever 304 counterclockwise to retract the wedge 300 against the action of spring 307. By the time the wedge 300 is clear of the work, a lug 317 carried by lever 304 will have been moved above the hook 318 of a latch lever 319 pivotally supported at 320 by the bracket member 259a. Then a spring 321 effects counterclockwise movement of the latch 319 to cause its hook 318 to move under the lug 317 so as to retain the lever in wedge disengaging position preparatory to indexing the workholder. After the next indexing, when the screwdriver sleeve 242 descends it moves a rod 322 downwardly to cause its lower end to engage latch lever 319 to effect a clockwise movement thereof to cause the latch hook 318 to be retracted from the lug 317 to permit the spring 307 to move the lever 304 clockwise to move the wedge 300 into operating position.

In case the screw catcher 250 does not release the screw at the time in the machine cycle when the screwdriver blade should move up, the blade will be held down because the screw will hold the screw catcher down. Therefore sleeve 266 will be held down and sleeve 242 can not move up because the flange 271 of sleeve 266 is engaged by a hook bar 330 which is screw 331 attaches to clamp bracket 267 (Fig. 39), there being a slot 332 in bar 330 which receives screw 331 and thus provides for its vertical adjustment. If at a certain time before the next indexing the screwdriver blade is held down, an electrical control to be described is operated for the purpose of causing pressure fluid to be admitted to the right end cylinder C4 (Fig. 32) supported by a bracket 335 and containing a piston connected by a rod 336 with a clevis 337 which a link 338 connects with a lever 339 pivotally supported at 340 by bracket 335 and connected with a lever 341 having a yoke 342 the branches of which carry pins 343 received by grooves 344 of the block 256. Therefore the levers 339 and 341 are moved counterclockwise to cause block 256 to be lifted and also the sleeve 266 in order to insure that the portion 256a of smaller diameter of block 256 is above the bosses 255

of the screw catcher blades. The screw catcher having been released by a left movement of piston rod 336 (in case it had not been released normally), a spring in cylinder C3 will effect retraction of screwdriver blade and restoration of the screwdriver parts to normal position as shown in Fig. 32. When block 256 has arrived at the upper limit of its movement, a screw 350 carried by lever 339 engages the plunger 351 of switch SW8 at station 8 (SW9 at station 10) to effect a circuit control which causes admission of pressure fluid at the left end to the cylinder C4 to effect right movement of rod 336 and down movement of the block 256 to normal position preparatory to the next operation of the screwdriver.

The circuit which controls admission of pressure fluid to the right end of cylinder C4 for the purpose of lifting the block 256 to force release of the screw catcher after the screw has been threaded is under control by switch SW6 at station 8 (SW7 at station 10) mounted on a bracket 352 providing a pivot 353 for a lever 354 which is urged counterclockwise by a spring 355 surrounding a rod 356 the head of which is above a rib 357 of lever 354 and the shank of which extends through spring 355 and through the bracket 352 and receives nuts 358. The free end of lever 354 is engageable by a pin 359 carried by an arm 243. Normally, when the screw catcher operates automatically to release the screw, the arm 243 will have moved to its upper position before the next indexing operation thereby permitting the spring 355 to move lever 354 into position for causing a screw 360 carried by lever arm 361 to engage plunger 362 of switch SW6 (or SW7) to cause this switch to open. If this switch is open at a certain time before the next indexing, no pressure fluid will be admitted to the right end of cylinder C4. But if at a certain time before the next indexing, switch SW6 (or SW7) remains closed due to the fact that arm 243 could not rise because the screw catcher did not release the screw, a circuit will be completed to admit pressure fluid to the right end of cylinder C4 to lift the block 256 as described.

Whenever block 256 is raised by operation of rod 336, the bar 274 (Fig. 39) is raised with it so that sleeve 266 can move up without interference by bar 269 because, at that time, its projection 270 is under the flange 271 of sleeve 266 and it is necessary that the surface 277 of bar 274 be above the projection 272 of bar 269 so that this bar is free to swing away from the flange 271 of sleeve 266.

If considered to be necessary, the brush holders 10 may be pressed against workholder plates 47 (one being shown in Fig. 32) by fingers 365, 366 by a spring 367 connecting them with a post 368. Fingers 365, 366 extend from a hub 369 pivoted at 369a on a bracket 374 and having an arm 370 connected by a link 371 with a lever 372 pivoted at 373 on bracket 374 and carrying a pin 375 received by a slot 376 in a link 377 connected at 378 with lever 286 which, as shown in Fig. 32, causes the station centering rod 58 to be received by plate 291 on lever 290. Before indexing, during retraction of plate 291 from pin 58 the lever 286 operates through link 377, lever 372, link 371 and lever 370 to separate the fingers 365, 366 from the workholders.

Figs. 32 and 39 show the location of the station centering parts including 286, 289, 290, 290a, 291 for the No. 1 screwdriver at station 8 which applies and threads a screw into a brushholder on the front member 31 (lower in Fig. 4). Because the No. 2 screwdriver at station 10 operates upon the work upon the rear member 31 (upper in Fig. 4), the station centering parts 286, 289', 290' and 290a' are located as shown in Fig. 44 so that the plate corresponding to plate 291 (Fig. 32) will be properly located so that its notch (similar to notch 292, Fig. 32) will be engageable with the rod 58 of the workholder 20. At station 10, roller 316 (Figs. 32 and 39) is located at 316' (Fig. 39).

11

Station 11—lower workholder pins

By the mechanism shown in Figs. 45–48, the pin rods 35 are lowered preparatory to unloading the assembled work from the workholder. A bracket 380 (Fig. 45) supports a cylinder C5 containing a piston connected with a rod 381 connected with a plate 382 which carries bushings 383 which receive guide rods 384 attached to the bracket 380. Plate 382 supports two pairs of pullers, each pair comprising members 385 and 386.

Before an indexing operation, pressure fluid is admitted to the lower end of cylinder C5 to elevate the pullers 385, 386 to the position shown in Fig. 45 so that the flanges 35f of the rods 35 will be received between the pullers as shown in Fig. 45. After the indexing operation, pressure fluid is admitted to the upper end of cylinder C5 to cause plate 382 to move down and the pullers 385, 386 to engage the flanges 35f of rods 35 to move said rods into the position shown in Fig. 48. This lowers the rods and their pins 36 so that they are clear of the brush holders. After this operation and before the next indexing operation, pressure fluid is admitted to the lower end of cylinder C5 to cause the pullers 385, 386 to move up into the position shown in Fig. 45.

Station 12—unloading

Referring to Figs. 49–52, a bracket 390 supports a cylinder C6 containing a piston connected by a rod 391 with a plate 392 which is connected, as shown in Fig. 52, with two rods 393 which are guided by a bracket 394. Each rod 393 provides a socket for receiving a spring 395 which is confined under compression between a bushing 396 threaded into the rod 393 and the head flange 397 of a pin 398 which extends through a larger diameter hole in the bushing 396. The spring causes 35 the flat end surface of the rod head 397 to bear against a surface of the rod 393 which is at right angles to its direction of movement. When the workholder is at the unloading station, the two rods 398 will be substantially in alignment with the holes x (also Fig. 5) of the workholders as shown in Fig. 50. In case the rods 398 are not in exact alignment with these holes, they will be tilted slightly by virtue of engagement of the rounded ends of the rods with the walls of the workholders which provide the holes x. The larger hole 396a, receiving the rod 398, allows the rod 398 to tilt slightly. The rods 398 are located so as to pass through holes x and engage arms of the brush holders 10 and push the brush holders 10 from the work holders.

The bar 392 is integral with or connected with a plate 400 having a slot 401 which receives the shank of a stud 402 which is attached to the bracket 394. The plate 400 provides pushers 403 which are located vertically above the pins 398. Pushers 403 are located in alignment with brushes on the brush holder. When pressure fluid is admitted to the right end of cylinder C6 the rods 398 and the pushers 403 move to the left in Fig. 49 to effect unloading of the work by virtue of engagement of the rods 398 with the brush holders 10 and engagement of the pushers 403 with the brushes 12.

Station 13—workholder cleanout

Referring to Figs. 53–55, at station 13, there is located a hood 410 which is supported by a duct 411 connected with an exhaust fan. When the workholders arrive at station 13, under the hood 410, a solenoid S7 is energized to cause an opening of the valve 412 to connect a pipe 413 connected with a compressed air source with a nozzle 414 which directs a blast of air upon the workholders to clean them. The removed particles are sucked from the hood 410 and through the duct 411 to a dust collector. If it should happen that the brush holder assembly had not been unloaded from the front workholder, during the next indexing operation, that brush holder will engage a lug 415 projecting

12

from a plate 416 hingedly supported at 417 by the hood 410. The plate 416 is normally held in the position shown in Figs. 53 and 55 by spring 418 which surrounds a rod 419 guided by bracket 420 and attached to a clevis 421 connected by a pin 422 with plate 416. The spring 418 is confined under compression between the bracket 420 and the clevis 421. A brush holder remaining upon the front workholder will engage the lug 415 and cause the plates 416 to move clockwise as viewed in Fig. 53, thereby causing arm 423 thereof to move away from the plunger 424 of a switch SW15 to permit the switch to close to operate a signal, such as a bell, to warn the attendant that a workholder is not unloaded so that he may attend to the unloading manually. The plate 416 and the associated parts comprise the first unloading checker.

Station 14—second unloading checker

If the attendant fails to heed the warning signal or the warning signal fails to operate, the unloaded workholder will pass the station 14 where, as shown in Fig. 56, there is a lever 430 pivoted at 431 and urged clockwise by a spring 432 against a stop 433 and against the plunger 434 of a switch SW14 so that this switch is normally open. As the unloaded workholder passes station 14, parts of the unloaded assembly will engage the lever 430 and cause it to move counterclockwise in Fig. 56 to permit the closing of switch SW14 by a spring in the switch. As described hereinafter, when switch SW14 closes, a circuit is established which causes a bell to ring and the machine to stop.

In Fig. 57, cam shaft 105 rotates counterclockwise at cam 440 engaged by a roller 441 carried by a lever 442 pivoted at 443 and urged counterclockwise by a spring 444. From 240° to 310° of cam shaft rotation (Fig. 65), cam 440 causes opening of a valve 445 for causing pressure fluid to enter the lower end of cylinders C2 (Fig. 22) at each of the washer feeder stations 5 and 6, if washer feeders are used. At other times, valve 445 is conditioned for admission of pressure fluid to the upper end of cylinder C2.

In Fig. 59, a cam 450 rotated counterclockwise by cam shaft 105, causes, by means of mechanism like that shown in Fig. 57, the opening of a valve 451 during about 115° to 130° of cam shaft rotation (Fig. 65) to cause the lower end of cylinder C1 at station 2 (Fig. 22) to receive pressure fluid, to the upper end of cylinder C5 at station 11 (Fig. 45) and to the right end of cylinder C6 at station 12 (Fig. 49), to effect respectively, raising pins 36, lowering pins 36 and unloading the workholders. At other times, the pin raising, pin lowering and work unloading devices are retracted.

In Fig. 58, a cam 455 rotated counterclockwise by cam shaft 105, effects, through a cam roller 456 and a lever 457, the momentary opening of a switch SW11 at about 300° (Fig. 65) and the momentary closing of a switch SW10 at about 315° of cam shaft rotation.

In Fig. 60, a cam 460 rotated counterclockwise by cam shaft 105, effects, through a cam roller 461 and a lever 462, closure of a switch SW2 from about 140° to about 265° (Fig. 65) and momentary opening of a switch SW5 at about 315° of cam shaft rotation.

In Fig. 61, a cam 465 rotated counterclockwise by cam shaft 105, effects, through a cam roller 466 and a lever 467, the closure of a switch SW16 during about 130° to 300° of cam shaft rotation.

Electrical controls

In Fig. 62, the parts of various relays included in Figs. 63 and 64 and their circuit connections are shown diagrammatically.

Referring to Fig. 63, A. C. source wires 471, 472, 473 are connectible by switch SW1 with wires 481, 482, 483 which, by energizing relay PR1 are connected by contacts PR1a, b, d with motor M1 which operates the

conveyor and cam shaft and which, by energizing relay PR2 are connected by contacts PR2a, b, d with screwdriver operating motors M2 and M3. If washer feeders are used, then hopper-feed driving motors would be connected in a similar manner by a relay like PR2.

Wires 481 and 483 are connected with primary winding p_1 of a transformer TR1 whose secondary winding is connected with wires 501 and 502.

Circuit I, the starting control circuit for motor M1 includes wire 501, switch PB1a, wire 503, switch PB1b, air pressure responsive switch PS1, overload thermal switches t_1 (heated by heater resistances h_1 associated with motor M1) and, in parallel, coil PR1c of relay PR1, lamp L1, and wire 503. When compressed air is turned on for operation of air servos of the machine switch PS1 closes. Closure of switch PB1a causes energization of coil PR1c and relay contacts PR1a, b, d close to cause operation of motor M1, and contacts PR1c close to bypass switch PB1a so that it may be released for spring opening. Lamp L1 burns to indicate operation of motor M1. Motor M1 stops when switch PB1b is opened, or when either of overload switches t_1 open or when air supply is turned off and switch PS1 opens.

Circuit II, the starting control circuit of motors M2 and M3, is similar to circuit I and is completed by closing switch PB2a. It is interrupted by opening of switches PB2b or thermal overload switches t_2 or t_3 . A circuit similar to circuit II would be used to control washer feeder hopper feed motors if washer feeders are used.

The conveyor and cam shaft are mechanically connected with motor M1 by closing switch PB3a in circuit III which energizes solenoid S1 which moves the starting control lever to start position. The conveyor and cam shaft are mechanically disconnected from motor M1 by energizing solenoid S2. This can be effected by closing switch PB3b in circuit IV or by closing of relay contacts R8a in circuit IVA or by closing of relay contacts R7a in circuit IVB. Contacts R7a are closed when coil R7c (circuit V) of relay R7 is energized by closure of switch SW14 at station 14. Closure of switch SW15 (circuit VI) at station 13 causes ringing of bell 490. Closure of switch SW14 at station 14 effects closure of contacts R7b in circuit VIA and bell 490 rings again to warn the attendant that the work was not unloaded at station 13 and the machine stops.

After indexing (about 140°, Fig. 65) cam 460 closes switch SW2 (circuit VII) to effect energization of relay coils R1c and R2c. Relays R1 and R2 close their contacts R1a (circuit VIII) and R2a (circuit IX) to effect energization of solenoids S3 and S4 which cause operation of the screwdrivers at stations 8 and 10 and to effect energization of production counter operating solenoids S5 and S6 associated with the screwdrivers. R1c is energized provided relay contacts R5a remain closed, and R2c is energized provided relay contacts R6a remain closed. In a manner to be described, contacts R5a and R6a are opened if, respectively, the workholders at preceding stations 7 and 9 are not loaded.

Referring to Fig. 64, when cam 455 closes switch SW10 (circuit X) at 315° (Fig. 65), if feeler switch SW3 is then closed because the workholder at station 7 is not loaded, coil R5c is energized and relay R5 opens contacts R5d and locks in by closing contacts R5b (circuit XI) and opens contacts R5a (circuit VII) so that, after the following index when the holder is at station 8, coil R1c will not be energized when switch SW2 closes at about 140° (Fig. 65). Therefore the screwdriver at station 8 does not operate. If feeler switch SW4 (circuit XA) were closed when switch SW10 closes because the holder at station 9 was not loaded, coil R6c is energized to cause relay R6 to open contacts R6d and to lock itself in by closing contacts R6b (circuit XIA) and opens contacts R6a (circuit VII) so that, after the following index when the holder is at station 10, coil R1c will not

be energized when switch SW2 closes. Therefore the screwdriver at station 10 does not operate.

If switch SW12 (circuit XB) is closed when switch SW10 closes because the pins 36 of the workholder at station 7 would not go down when they should, coil R9c is energized and lamp L2 burns. Contacts R9b open and contacts R9d (circuit XIIB) close to lock in relay R9 and contacts R9a (circuit XIII) close to effect energization of coil R8c of relay R8 whose contacts R8a (circuit IVA) to effect energization of machine stopping solenoid S2. Burning of lamp L2 indicates that the holders at station 7 need cleaning out and lubricating so that their pins 36 will go down when they should.

If switch SW13 (circuit X-C) is closed when switch SW10 closes because the pins 36 of the workholder at station 9 would not go down when they should, coil R10 is energized and lamp L3 burns. Contacts R10b open and contacts R10d (circuit XIIC) close to lock in relay R10 and contacts R10a (circuit XIII) close to effect energization of coil R8c to effect machine stopping. Burning of lamp L3 indicates that the holders at station 9 need cleaning out and lubricating so that their pins 36 will go down when they should.

When switch SW11 opens at about 300° (Fig. 65) relays R5 and R6 are deenergized if they had been previously energized.

When the lever 133 (Fig. 19) is moved by solenoid S2 (when energized) to stop position, switch SW19 closes to complete circuit XII and coil R11c of relay R11 is energized to close its contacts R11b (circuit XIIA) so that coil R11c is locked in, and to open its contacts R11a (circuit XIII) so that coil R8c is deenergized and relay R8 returns to normal status and solenoid S2 is deenergized. When the lever 133 is moved to start position 35 by energizing solenoid S1, switch SW18 (circuit XIIA) opens momentarily and coils R11c, R9c and R10c are deenergized so that relays R11, R9 and R10 return to normal status.

When switch SW16 (circuit XIV) is closed by cam 465 between 130° and 300° (Fig. 65) solenoid S7 is energized and a blast of air issues from a nozzle at station 13 to clean the workholders.

If, when switch SW5 (circuit XV) is closed by cam 460 at about 320° (Fig. 65), the screwdriver at station 8 has not returned to up position, switch SW6 remains closed and coil R3c is energized. If the screwdriver at station 10 has not returned to up position when switch SW5 closes, switch SW7 remains closed and coil R4c is energized.

Circuit XVI includes the primary winding p_2 of a transformer TR2 whose secondary in circuit XVIA supplies wires 531 and 532.

When coil R3c is energized, relay R3 closes contacts R3a (circuit VXII) and solenoid S8 is energized to effect release of the screw 17 by the screw catcher at station 8. At the end of the screw catcher releasing operation, switch SW8 (circuit XVIII) closes to cause energization of solenoid S9 which causes the screw catcher at station 8 to return to normal status.

When coil R4c is energized, relay R4 closes contacts R4a (circuit XIX) and solenoid S10 is energized to effect release of the screw 17 by the screw catcher at station 10. At the end of the screw catcher releasing operation, switch SW9 (circuit XX) closes to cause energization of solenoid S11 which causes the screw catcher at station 10 to return to normal status.

While the embodiment of the present invention as herein disclosed, constitutes a preferred form, it is to be understood that other forms might be adopted.

What is claimed is as follows:

1. A machine for making an assembly comprising a brush holder, a brush, a terminal clip having a lead wire extending therefrom, and a screw extending through holes in the clip and brush and threadedly engaging the brush holder, said machine comprising a plurality of

workholders each providing for reception of a brush holder, a pin means movably mounted on each workholder and located so as to be in alignment with a hole in the brush holder when said brush holder is placed upon the workholder and said means being adapted to move from a position in which it clears the brush holder to a position in which it extends through and beyond the brush holder to be received by a hole in the brush when placed next to the brush holder and to be received by a hole in the terminal clip when placed next to the brush, a conveyor for moving the workholders successively to stations, means for indexing the conveyor, means at a station for moving the pin means through a brush holder placed upon the workholder, said pin means serving to locate the brush and terminal clip which are successively placed next to the brush holder and brush respectively, and a power driven screwdriver at a succeeding station for locating a screw in alignment with the pin means and for causing the screw to push the pin means as the screw is passed through the holes in the terminal clip and the brush and is threaded through a hole in the brush holder. 20

2. A machine according to claim 1 having means at a station following the screwdriver station for retracting the pin so that it does not contact the brush holder and means at station following the pin retracting station 25 for ejecting the assembly from the workholder.

3. In a machine for making an assembly comprising a brush holder, a brush, a terminal clip having a lead wire extending therefrom, a lock washer and a screw extending through holes in the lock washer, clip, and 30

brush and threadedly engaging the brush holder, said machine comprising a plurality of workholders each providing for reception of a brush holder, a pin means movably mounted on each workholder and located so as to be in alignment with a hole in the brush holder when said brush holder is placed upon the workholder, said pin means being adapted to move from a remote position wherein it is out of contact with the brush holder to a second position wherein a portion thereof extends through and beyond the brush holder and through a hole in a brush when said brush is placed next to the brush holder and through a hole in a terminal clip when said clip is placed next to the brush and to extend through a lock washer when said washer is placed next to said terminal clip, and means at a station for moving the pin means to said second position. 15
